HASSOCK

Phillip K. Raiford, Memphis, Tenn., assignor to Shoe House, Inc., Memphis, Tenn., a corporation of Tennessee

Filed Oct. 20, 1965, Ser. No. 87,631

Term of patent 14 years

(Cl. D15—8)

FIG. 1

FIG. 2

FIG. 3

FIG. 4

FIG. 5

FIG. 1 is a side perspective view of a hassock embodying my new design.

FIG. 2 is a plan view thereof.

FIG. 3 is an inverted plan view thereof.

FIG. 4 is a view in rear elevation.

FIG. 5 is a view in front elevation.

The side of the hassock which appears in FIG. 1 is a mirror image of the opposite side.

I claim:

The ornamental design for a hassock, as shown.
